Atty.

E. R. HALL, OF MEXICO, NEW YORK.

Letters Patent No. 89,217, dated April 20, 1869.

IMPROVEMENT IN WOOD-SAWING MACHINE.

The Schedule referred to in these Letters Patent and making part of the same.

To all whom it may concern:

Be it known that I, E. R. HALL, of Mexico, in the county of Oswego, and State of New York, have invented a new and valuable Improvement in Wood-Sawing Machines; and I do hereby declare that the following is a full, clear, and exact description of the construction and operation of the same, reference being had to the annexed drawings, making a part of this specification, and to the letters and figures of reference marked thereon.

Figure 1 of the drawings is a sectional view of my wood-sawing machine, and

Figure 2 is a detail.

My invention has relation to devices for sawing wood, and

It consists mainly in providing and arranging more efficient and perfect means for that purpose than have heretofore been invented.

To this end, I construct a frame, in a quadrangular form, with an upright post at each corner, all united by end and side-bars, as shown on the drawings.

On the top of these corner-posts, respectively, I adjust grooved caps, marked A on the drawings, adapted to hold and regulate the movements of the saw-frame, hereinafter mentioned.

The letter B is the saw-frame, adjusted in the grooves of the caps A, and which is moved back and forth by the devices hereinafter specified.

A second frame, C, is attached to the main frame, in the manner shown on fig. 1, extending forward from the front of the main frame, and serves as a rest and support for the wheels, journals, and cranks, next described.

The letter D represents a large cogged wheel, the cogs of which are attached to its inner sides, and point downward, as shown.

This wheel is connected with a side-arm of the frame C by a short journal working therein, and constitutes the driving-wheel of my device, and which may be operated by a crank on its side, or a belt on its periphery.

The letter E is a pinion, attached to the end of the shaft a. It has cogs on its periphery, working with the cogs on the wheel D.

The shaft a extends inward to a point a little less than midway between the side-arms of the frame C, where it is united with the crank G.

A shaft, corresponding in length and size with the shaft a, reaches from the opposite side of the crank G beyond the opposite side of the frame C, where it is

secured to and operates a fly-wheel of the usual construction.

The journals upon which these shafts rotate are placed on the tops of the side-arms of frame C.

The letter c is a pitman, connecting the crank G with the saw-frame B, in the manner shown.

The letter d is a shaft, adjusted in arms extending rearward from the front posts of the main frame, so arranged that it may rotate partly around therein, the object of which is to support and aid in the movements of the saw-horse, next mentioned.

The saw-horse is marked H on the drawings, and it is arranged in such manner that the wood may be forced upward to the saws, instead of remaining stationary, as is usual in such devices.

The wood is forced upward to the saw by lifting the horse upon which it rests.

The letter L represents a bent lever, firmly attached to the horse, in the manner shown, and extending forward of the frame C.

This lever is connected with the shaft d, as shown, by a ring and staple, or other suitable device, and the V-shaped extension of the saw-horse is also connected with said shaft, in the manner represented on fig. 2.

When the wood to be sawed is in place, a hook s, hinged to the saw-horse, is thrown over the same, and holds it securely in the crotch of the saw-horse.

It will readily be seen that any desirable number of saws may be adjusted in the saw-frame, but I usually place two only therein, at such distance from each other as may be required to saw the wood of the desired length.

The operator raises the wood to the saw by pressing down upon the extreme end of the lever L.

What I claim as my invention, and desire to secure by Letters Patent, is—

A sawing-machine, for wood, having main frame and frame C, as described, grooved caps A, saw-frame B, wheels D and E, shafts a and d, crank G, pitman c, lever L, saw-horse H, and hook s, when each part is constructed, arranged, and operates as described.

In testimony that I claim the above, I have hereunto subscribed my name, in the presence of two witnesses.

E. R. HALL.
